UNITED STATES PATENT OFFICE

155,104

DESIGN FOR A DOLL

Jane Prendiville, New York, N. Y.

Application October 9, 1947, Serial No. 141,821

Term of patent 7 years

(Cl. D34—4)

To all whom it may concern:

Be it known that I, Jane Prendiville, a citizen of the United States of America and a resident of the city of New York, in the county of New York and State of New York, have invented a new, original, and ornamental Design for a Doll, of which the following is a specification, reference being had to the accompanying drawing, forming a part thereof:

Fig. 1 is a front view of a doll, showing my new design.

Fig. 2 is a rear view thereof.

Fig. 3 is a side view thereof on an enlarged scale.

I claim:

The ornamental design for a doll, substantially as shown.

JANE PRENDIVILLE.
